APPARATUS FOR TRANSMITTING
INTELLIGENCE

Samuel Brand, Binghamton, and Herman J. Klotz, Endicott, N. Y., assignors to International Business Machines Corporation, New York, N. Y., a corporation of New York

Application April 11, 1944, Serial No. 530,510

7 Claims. (Cl. 178—33)

This invention relates generally to apparatus for transmitting intelligence, and more particularly to apparatus which is controlled by a desired source of intelligence, such for example as a record having character representations recorded therein according to a selected code system, and which operates to transmit such intelligence, or to store such intelligence for future transmission, to a suitable manifesting means and therein manifest such intelligence in a desired form.

According to one aspect of the present invention a principal feature thereof may be considered as being the provision of apparatus for transmitting intelligence which comprises generally a magnet mounted for rotation about a fixed axis, a means for effecting rotation of the magnet about its axis, a plurality of armatures spaced circumferentially about the axis and so positioned that as the magnet rotates, the latter occupies successively attracting positions with respect to the armatures. The apparatus also comprises a means which is controlled by a source of intelligence, such as a prepared record, and which is operable to selectively energize the magnet as the latter successively occupies attracting positions with respect to the armatures so as to provide thereby different conditions of selective actuation of the armatures, which conditions represent, respectively, different characters in accordance with a code system. The apparatus also includes a character manifesting means controlled by the armatures and operable during each revolution of the magnet to manifest the character represented by the condition of selective actuation of the armatures.

An object of this invention is to provide apparatus for transmitting intelligence, which is of improved construction and arrangement of parts and which is highly effective and efficient in operation.

A further object is to provide apparatus of the above type which is composed of relatively few parts and which is relatively compact in construction.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a side elevational view showing the invention as embodied in record controlled apparatus.

Fig. 2 is a vertical section taken on the line 2—2 of Fig. 1, the magnet being omitted from this view to facilitate understanding of other parts of the apparatus.

Fig. 3 is an enlarged fragmentary section taken on the line 3—3 of Fig. 2.

Fig. 4 is an enlarged fragmentary section on the line 4—4 of Fig. 2, and showing the details of construction of a one-revolution clutch forming a part of the illustrative embodiment, the clutch pawls being shown as held in declutched position where the driving and driven elements are disconnected.

Fig. 5 is a view like Fig. 4, and showing the clutch pawls as held in clutched position where they lock the driving and driven elements together for rotation in unison.

Fig. 6 is an enlarged fragmentary section of the clutch taken on the line 6—6 of Fig. 4.

Fig. 7 is a side elevational view of the record controlled apparatus and illustrating the side opposite to that shown in Fig. 1 and disclosing the record feeding and sensing means.

Fig. 8 is an enlarged fragmentary section taken on the line 8—8 of Fig. 7 and showing in bottom plan the record sensing elements.

Fig. 9 is a fragmentary detail view showing one of the contact latch armatures and its associated contact carrying lever which form a part of the preferred embodiment, the armature and lever being shown in unlatched relation.

Fig. 10 is a fragmentary detail view showing in latched position the clutch latch armature and a portion of the secondary latch lever controlled thereby.

Fig. 11 is a view showing one example of a record bearing tape prepared for use with the embodiment of the invention disclosed herein.

Fig. 12 is a view showing somewhat diagrammatically certain of the operating elements of the record controlled apparatus, the view also including a wiring diagram of the controlling circuits of the apparatus and an example of a translator circuit network forming a part of the character manifesting means of the apparatus.

Fig. 13 is a chart to be used in connection with Fig. 12.

The apparatus for transmitting intelligence which is disclosed in the accompanying drawings as being one preferred embodiment of the present invention, is shown as being controlled in its operation by a prepared record sheet or tape, wherein characters are separately represented according to a selected code system by differential location of code designations at a predetermined num-

ber of index point positions. While in so far as certain of the broader aspects of the present invention are concerned, the invention might be embodied in apparatus which is controlled by other sources of intelligence and while the apparatus disclosed might be readily adapted for use with various other kinds of prepared records bearing character representations, the apparatus disclosed herein is shown as being controlled by a prepared record of the type disclosed in the United States Patent to Samuel Brand, No. 2,209,106, granted July 23, 1940.

Before describing in detail the construction and operation of the apparatus disclosed in the accompanying drawings, it is believed that it will be helpful to consider first one example of a record tape wherein characters are represented in the same manner and according to the same code as is disclosed in the Brand patent, just identified. Such a prepared record is shown in Fig. 11 hereof, wherein a portion of a tape 10 is shown as bearing a plurality of characters 11 representing by way of example the digits "0" through "9." As explained in the above mentioned Brand patent, the characters 11 may be suitably applied to the tape by a typewriter having type of the desired shape and using an ink which conducts electricity. The characters are arranged in a column running lengthwise of the tape; and, when the apparatus disclosed hereinafter is operating, the tape is fed lengthwise, as indicated by the arrows in Fig. 11, past a relatively stationary sensing station 12 comprising transversely spaced sensing elements 13 and 14 (see Figs. 7 and 8), and in such a manner that the characters are scanned progressively from top to bottom.

Also, as is explained in the Brand patent identified above, the characters 11 are specifically formed as legible variations of conventional shapes, so that each character includes as a part thereof one or more horizontally disposed portions or bars 15. The length of each bar is such that, when the tape is fed past the sensing elements 13 and 14, such bar will contact simultaneously the two sensing elements and thereby close a sensing circuit. The remaining portions of the characters 11, such as the relatively short horizontal portion forming a part of the digit "3" and also the vertical and angular portions forming parts of most of the characters, cannot be contacted simultaneously by the sensing elements 13 and 14 and hence they cannot function to close the sensing circuit. The sensing elements are indicated diagrammatically in Fig. 11, and the width of the zone scanned by the sensing elements is indicated by the spaced parallel dot-and-dash lines 16 extending lengthwise of the tape.

The horizontal bars 15 form code designations of a selected combinational code having five index point positions and wherein each character is arbitrarily represented by differential location of the bars 15 in the five index point positions. For the purposes of a better understanding of the present invention, the five index point positions for each character representation are indicated in Fig. 11 by five equally spaced horizontal lines 17.

In the formation of the characters 11 the number of the horizontal bars 15 for each character representation and the differential positioning of such bars in the index point positions 17 for such character representation comprise variables in the preselected code, whereby the individual

characters are differentiated from one another by different combinations of these two variables. It is noted that in each character representation, a bar 15 is located in the first index point position thereof to be sensed. Thus, the bar 15 in the first index point position of each character representation determines the beginning of such representation. The digit "4" is shown as being represented by only one bar 15 which, as stated, is in the first index point position. The digits "0," "1," "7" and "9" are each shown as being represented by two bars 15. In each of these latter characters one bar 15 is in the first position and the other bar 15 thereof is spaced from the one bar a different number of index point positions. The digits "2," "3," "5," "6" and "8" are each shown as being represented by three bars 15. As before, the first bar 15 to be sensed of each character representation is located in the first index point position, but the other two bars 15 are differentially located in the remaining index point positions of each such character.

In accordance with the one preferred embodiment of this invention which is disclosed in the drawings, the apparatus comprises a means for successively sensing the index point positions 17 of each character representation 11 on the tape 10 in a predetermined order and at a predetermined rate and so as to determine the presence 25 of code designations, which are the bars 15, in the index point positions 17. The latter means 30 comprises a mechanism for feeding the tape 10 past the sensing elements 13 and 14 at a predetermined uniform rate.

As shown in Fig. 7, the tape feeding mechanism comprises a feed roller 20 rotatably mounted on a stud 21 carried by a base or support plate 22. The roller 20 is fixed to a gear 23 which is arranged coaxially therewith and is also rotatably mounted on the stud 21. The gear 23 meshes with a second gear 24 fixed on a suitable power or drive shaft 25 journaled in the support plate 22. The power shaft 25 is adapted to be continuously rotated at a uniform rate by any 45 suitable means such, for example, as by an electric motor (not shown).

The sensing elements 13 and 14 are mounted on a suitable carrier or frame 27 which is pivoted on a stud 28 projecting from the support plate 50 22. An idler pressure roller 29 is journaled on a stud 30 also carried by the frame 27, and serves to engage and hold the tape 10 firmly in engagement with the feed roller 20 and thereby cooperates with the roller 20 in feeding the tape.

As shown in Figs. 2, 7 and 8, each of the sensing elements 13 and 14 is formed by a pair of conductive flat metal plates 32, and the several plates 32 are arranged in parallel side-by-side 60 relation and are pivoted at one set of their adjacent ends on a common stud 33 which is formed of a suitable insulation material and is also carried by the pivoted frame 27. The two plates 32 which compose the element 13 are centrally arranged in side-by-side contact with one another as shown in Fig. 8. The two plates 32 forming the sensing element 14 are arranged, respectively, on opposite sides of the centrally positioned plates 32 of the element 13, and each plate 32 65 of the element 14 is separated from the adjacent plate of the element 13 by a flat strip 34 of a suitable insulation material. The strips 34 are also pivoted on the stud 33.

The two flat strips 34 of insulation are held 70 in their operative position between the sensing

elements by a pair of spring fingers 35, respectively. The fingers 35 are joined together at one end and are fixed to an upstanding post 38 of insulation material carried by a bracket 36 also formed of insulation material and secured to the frame 21. The two outer ends of the fingers 35 engage, respectively, upstanding portions 37 of the strips 34 and thereby hold the latter in engagement with the tape 18.

Each of the plates 32 forming the sensing elements 13 and 14, is provided with an integral depending sensing projection 39 which engages the tape as the latter is being fed lengthwise by the roller 20. The projections 39 on the two outside plates 32 of the element 14, are held against the tape by the outer ends of two spring fingers 40, respectively. The two fingers 40 are formed of a suitable conductive metal and engage, respectively, the top of the two outside plates 32. The fingers 40 are joined at their other or inner ends by a conductive metal strip 41 formed integral with the fingers 40 and fixed by screws 42 to the bracket 38. One of the screws 42 serves as a terminal for a lead wire 44 of the sensing circuit.

The two centrally disposed plates 32 which constitute the other sensing element 13, are formed, respectively, at the ends thereof which are pivoted to the stud 33, with integral upstanding lever arms 45. One end of a tension spring 46 is connected to the upper ends of the arms 45 and the other end of the spring is connected to a stud 47 mounted on the frame 21. The spring 46 serves as a means for holding the depending sensing projections 39 of the plates 32 forming the element 13, in contact with the moving tape and also serves as an electrical conductor connecting the two plates 32 with the stud 47. The other lead wire 48 of the sensing circuit may be connected to the stud 47.

In accordance with the disclosed embodiment of the present invention, the improved apparatus also comprises a single selector magnet 50 (see Fig. 1) which is mounted for rotation about a fixed axis. The apparatus also comprises a means which provides a driving connection between the magnet 50 and the power shaft 25 so that the magnet 50 rotates synchronously with the feeding and sensing of the tape. The means which provides the driving connection is herein shown to be in the form of a one-revolution clutch 52 (see Figs. 2, 4, 5, and 6). As will appear more fully hereinafter, the clutch 52 is automatically engaged with the closing of the sensing circuit by the sensing of a bar 15 in the first index point position of each character representation. When engaged, the clutch 52 provides for the rotation of the magnet 50 by the power shaft 25 from the home or inactive position, the position shown in the drawings, for one complete revolution and then be disengaged upon returning to home position.

During each revolution of the magnet 50, all of the index point positions 17 of one character representation are successively sensed; and, as stated above, the rate of sensing is synchronous with the rate of rotation of the magnet. As will later appear, the construction of the clutch 52 is such that the magnet 50 commences its synchronous rotation while the sensing elements 13 and 14 are still contacting the bar 15 in the first index point position of a character representation.

As shown in Figs. 1 and 7, a gear 53 is fixed to the continuously rotating power shaft 25 at the side of the support plate 22 which is opposite to that supporting the above described tape feeding

and sensing means. The gear 53 meshes with a second gear 54 journaled on a stud 55 fixed to the plate 22 and the gear 54 meshes with a third gear 56 which is coaxially mounted on and fixed to the rotary driving element of the one-revolution clutch 52 (see Fig. 2). Thus, the driving element of the clutch is continuously rotated at a uniform rate by the power shaft and synchronously with the movement of the tape 18 past the sensing elements 13 and 14.

The driving element of the clutch 52 comprises a clutch disk 58 which is formed on its periphery with radially extending clutch teeth 59. The clutch disk 58 is journaled for rotation on a cylindrical hub 60 of a pawl carrier 61 which carrier forms the driven element of the clutch 52 and is, in turn, journaled for rotation on a stud 64 mounted on the support plate 22.

The pawl carrier 61 also comprises a circular disk 62 formed integral with one end of the central hub 60, and an annular rim portion 63 formed integral with the peripheral portions of the end disk 62 and overhanging the hub 60 to define with the latter an annular space receiving the clutch disk 58. The circular end disk 62 is provided with a pair of spaced parallel slots or grooves 65 and 66, respectively, which are located on opposite sides of the hub 60 and each groove extends in a chordal direction for the full width of the end disk 62 and is open at its two ends. The portions of the rim 63 which are contiguous to the two ends of each of the grooves 65 and 66 are also cut away and thereby form right-angle extensions of the ends of the grooves. The two right-angle extensions of the ends of groove 65 are indicated by 65a and 65b, respectively, and the two right-angle extensions of the ends of groove 66 by 66a and 66b, respectively (see Figs. 4, 5, and 6).

Slidably mounted within the groove 65 is a clutch pawl 68 formed with a body part slidably fitting within the portion of the groove 65 which extends as a chord across the end disk 62, and also comprising a pair of right angle end projections 68a and 68b adapted to slide within the groove extensions 65a and 65b, respectively. Likewise, a clutch pawl 69 slidably fits within the portion of the groove 66 extending as a chord across the end disk 62 and comprises right angle end projections 69a and 69b, respectively, adapted to slide within the groove extensions 66a and 66b.

The projection 68a of pawl 68 is shaped so that when it occupies the extension 65a of groove 65 it forms a pawl tooth 10. When the pawl 68 is slid to the right, as viewed in Figs. 4 and 5, the pawl tooth 10 is adapted to enter the space between adjacent clutch disk teeth 59 and thereby lock together the driving clutch disk 58 and the driven pawl carrier 61 for rotation in unison. Also, the projection 69b of pawl 69 is shaped so that when it occupies the extension 66b of groove 66, it forms a second pawl tooth 72. Thus, when the pawl 69 is slid to the left as viewed in Fig. 4, the tooth 72 is also adapted to enter the space between adjacent clutch disk teeth 59 and thereby clutch or lock together the clutch disk 58 and pawl carrier 61.

As will appear more fully hereinafter, means is provided which operates in response to the sensing of a bar 15 in the first index point position of a character representation, to move the pawl 68 to the right or toward its clutching position and to move the pawl 69 to the left or toward its clutching position. From an examination of Fig. 5, it will be observed that the cir-

cumferential spacing of pawl teeth 70 and 72 and the number of teeth 59 on the clutch disk 58 are so related that only one of the pawl teeth can fully engage a space between clutch disk teeth each time the clutch is engaged. The construction is such that when either of the pawl teeth fully occupies a space between clutch disk teeth, the position of the other pawl tooth is such that it is only partially within a space between clutch disk teeth. The purpose of providing two pawls and this particular spacing of the pawl teeth with respect to the clutch disk teeth, is to reduce to a minimum the time required to clutch the parts together after the sensing of the first bar 15 of a character 11. As stated previously, the clutch will be engaged while the sensing elements 13 and 14 are still in engagement with the bar 15 in the first index point position of a character representation.

In Fig. 5, the parts are shown clutched together with the pawl tooth 70 fully fitting between adjacent clutch disk teeth 58 and the pawl tooth 72 only partially within a tooth space. Fig. 4 shows the declutched position of the parts. The pawls 68 and 69 are moved from the declutched position of Fig. 4, to the clutched position of Fig. 5, and vice versa, by a pair of clutch latch rings 14 and 15, respectively, which are rotatably mounted on the cylindrical outer surface of the rim 63 of the pawl carrier 61 and are arranged in spaced side-by-side relation with respect to one another. The latch ring 14 actuates the pawl 68 and the ring 15 actuates the pawl 69.

The latch ring 14 is constantly urged to rotate in a clockwise direction, as viewed in Figs. 1, 3, 4, and 5, by a tension spring 76 connected at one end to an arm 77 extending from the ring 14 and at its other end to an arm 78 extending from a cam plate 79, the latter being fixed to the pawl carrier 61 (see also Fig. 2). Likewise, the ring 15 is constantly urged to rotate in a clockwise direction by a tension spring 81 connecting the outer end of an arm 82 extending from the ring 15 and the outer end of an arm 83 extending from the cam plate 79.

In Fig. 4, both clutch latch rings 14 and 15 are shown as being in their home or latched position, which is the position where they hold the pawls 68 and 69 out of clutching engagement with the clutch disk 58. The latch rings 14 and 15 are shown as being provided, respectively, with downwardly extending latching projections 85 and 86. The rings 14 and 15 are held in their latched position against the force of the springs 76 and 81 due to the engagement of their projections 85 and 86 with a bail 87, which bail forms a part of a secondary latch lever 88 and is disposed in the path of the latching projections 85 and 86 when the lever 88 occupies a latched position, the position shown in Figs. 1, 3, and 4.

The secondary latch lever 88 is pivoted intermediate its ends on a stud 90 carried by the support plate 22, and is held in latched position by an end projection 91 thereof engaging the face 92 of a notch 93 formed in the lower outer end 94 of a clutch latch armature 95 (see also Fig. 10). A tension spring 96 connecting the lever 88 and a fixed stud 97 on the support plate 22 holds the end 91 against the face 92 of the notch 93, and also moves the lever 88 counterclockwise and the bail 87 downward and out of latching position when the end 91 of the clutch latch armature 95 is moved to the left as viewed in Fig. 3.

The clutch latch armature 95 is formed as a

lever and is pivoted intermediate its ends on a stud 98 extending from the support plate 22. A tension spring 100 connecting a projecting arm 101 on the clutch latch armature 95 and the fixed stud 97, contributes in holding the ends 94 and 91, respectively, in their latching engagement shown more clearly in Figs. 3 and 10.

As shown in Fig. 3, a detent 104 is pivoted on a stud 105 projecting from the support plate 22, and engages a notch or recess 106 formed in the peripheral cam surface of the cam plate 79 and serves to position and hold the cam plate 79, and the pawl carrier and magnet which are fixed thereto, in the home or declutched position. A tension spring 107 connects an arm 108 on the detent 104 with the fixed stud 97 and urges the detent in engagement with the notch 106. It is apparent from an examination of Fig. 3, that when the detent 104 enters the cam notch 106, movement of the plate 79 in either direction is resisted by the force of the spring 107. Also, when the cam plate is moving clockwise as viewed in Fig. 3 and nears the home position, the spring 107 acting through the detent 104 and side 110 of the notch 106 urges the plate 79 forward and clockwise towards the home position.

As shown in Figs. 4 and 5, the latch ring 14 which actuates the pawl 68 is provided with a pair of operating notches 112 and 113, respectively, which are adapted to receive the end projections 68a and 68b of the pawl 68 during the clutching and declutching operation. The notch 112 receives the projection 68a when the parts are declutched (see Fig. 4), and the notch 113 receives the projection 68b when the parts are clutched (see Fig. 5). In Fig. 4, the pawl tooth 70 is shown as being held locked in declutched position by the engagement of an inner edge portion 114 of ring 14 with the outer surface of projection 68b.

As shown in Fig. 1, the magnet 50 is fixed to a bracket 115 projecting from the cam plate 79 which, as stated, is fixed to the driven pawl carrier 61. With magnet 50 at home position and when it is energized in a manner to be later described, the clutch latch armature 95 is attracted thereby and is pivoted clockwise about the stud 99, as viewed in Figs. 1 and 3. This moves the end 91 out of latching engagement with the end 91 of the secondary latch 88 and thereby permits the spring 96 to move the latch 88 counterclockwise and thereby disengage the bail 87 from the projections 85 and 86 of the two latch rings 14 and 15.

When the bail 87 of the secondary latch 88 is moved downward and out of engagement with the projection 85 of ring 14, the spring 76 rotates the ring 14 clockwise with respect to the carrier 61; and, in so doing, the notch 113 is moved opposite the projection 68b and so that the pawl 68 is no longer held in declutched position by the surface 114 of the ring 14. Also, as the ring 14 moves clockwise, an inclined cam face 116 of the notch 112 engages an outer inclined cam face 117 of projection 68a which carries the pawl tooth 70, and thereby moves the pawl 68 to the right as viewed in Fig. 4. If the position of the clutch disk is such that the pawl tooth 70 can fully engage a clutch disk tooth space, the clockwise rotation of the latch ring 14 will continue until the projection 68a is moved entirely out of the notch 112 and the projection 68b is moved into the notch 113 and is engaged by an inner side face 118 of the notch, which thereby stops further clockwise movement of the

ring 74. This is the clutched position shown in Fig. 5 where the pawl tooth 70 fits fully between teeth of the disk 58. It is noted that the pawl 68 is held locked in its clutched position by the engagement of an inner edge 119 of the ring with the outer surface of the projection 68a. 6

As shown in Figs. 4 and 5, the other latch ring 75 is provided with a pair of clearance notches 120 and 121 located alongside and registering, respectively, with the just described operating notches 112 and 113 of the ring 74 for all positions of the two rings. The pawl projections 68a and 68b also extend into the clearance notches 120 and 121 during operation of the ring 74, but the latter notches are of sufficient length and depth that the ring 75 cannot interfere with the actuation of the pawl 68 by the latch ring 74. 10

The other latch ring 75 is also provided with a pair of operating notches 124 and 125, respectively, which are adapted to receive the projections 69a and 69b of the other pawl 69 and are adapted to effect operation of the pawl 69 in the same manner as just described in connection with the operation of pawl 68 by the notches 112 and 113 of ring 74. The latch ring 74 is also provided with a pair of clearance notches 126 and 127 located opposite the notches 124 and 125, respectively, and for the purpose of preventing interference by the ring 74 of the operation of the pawl 69 by the notches 124 and 125. 20

When the pawl 69 is in its declutched position, as shown in Fig. 4, the inner edge 128 of the ring 75 adjacent the notch 124, engages the outer surface of the projection 69a and thereby holds the pawl in the position where the pawl tooth 72 on projection 69b occupies the notch 125 and is out of engagement with the clutch disk teeth 59. When the ring 75 is unlatched by the bail 87 moving downward in the manner previously explained the spring 81 rotates the latch ring 75 clockwise with respect to the carrier 61; and, as a result, the cam face 129 of the notch 125 engages the inclined outer surface 130 of the pawl projection 69b and thereby moves the pawl 69 and pawl tooth 72 to the left as viewed in Fig. 4. At this time the notch 124 will be opposite the projection 69a so that the latter can enter the notch 124 and permit the just described movement of the pawl 69. 25

In Fig. 5, the pawl tooth 72 is shown as being only partially within a tooth space of the clutch disk 58. This is because the pawl tooth 70 is fully within a space between clutch disk teeth. As explained previously, the circumferential spacing of the pawls and the clutch disk teeth is such that only one pawl tooth can fully engage a clutch disk tooth space during a clutching operation. It will be apparent that if it had so happened when the projections 85 and 86 were unlatched by the bail 87, that a clutch disk tooth space had been opposite the pawl tooth 72, instead of one being opposite the pawl tooth 70 as previously described, then the pawl tooth 72 would have fully entered a space between clutch disk teeth and the clutch ring 75 would have then continued to move clockwise with respect to the carrier 61 until the side 132 of notch 124 engaged the projection 69a, which would stop rotation of the ring 75. In the latter position, the inner edge 133 of ring 75 will engage the outer surface of projection 69b and hold the pawl 69 locked in clutched position. 30

As will be apparent from the foregoing, when the latch rings 74 and 75 are released by the bail 87 moving downward in response to the energizing of the magnet 50 in home position, the clutch 35

52 is immediately engaged, and the magnet immediately commences rotating in a clockwise direction, as viewed in Fig. 1. After the magnet has rotated slightly more than one half of a revolution, the peripheral cam surface of the cam plate 79 engages an end 135 of the secondary latch lever 88 and rotates the latter clockwise as viewed in Fig. 3, against the force of the spring 96, and so that the other end 91 thereof moves upward and into the notch 93 formed on the end of the clutch latch armature 95. The cam 79 is so designed that when the highest portion 136 of the cam is in engagement with the end 135 of the lever 88, the other end 91 is slightly above and past the latching face 92 of the notch 93. As the end 135 moves out of engagement with the highest portion 136 of the cam and into engagement with the face 110 of the notch 106, the secondary latch lever 88 is moved slightly counterclockwise and until the end 91 thereof engages the face 92 of the notch and thereby latches again the lever 88. The spring 100 maintains the end 94 of the clutch latch armature in engagement with the end 91 and thereby assures the just described latching operation. 40

With the latching of the secondary latch 88 in latched position, the ball 87 is again disposed in the path of movement of the projections 85 and 86 of the latch rings 74 and 75. Just before the magnet 50 reaches home position, the projections engage the bail 87 and further movement of the projections is prevented thereby. However, the pawl carrier 61 will continue to rotate until the pawl teeth 70 and 72 are completely disengaged from the teeth of disk 58. Considering Fig. 5 with the tooth 70 in full clutching engagement with the disk 58, rotation of the pawl carrier 61 clockwise with the ring 74 held stationary in the manner just explained, will result in the inclined cam face 140 of the projection 68b engaging the inclined cam face 141 of the notch 113 with the result that the pawl 68 will be slid to the left to disengage the tooth 70 from the disk 58. As the notch 112 will be opposite the projection 68a at this time the latter will enter such notch and the pawl carrier 61 will stop rotating with the parts in their respective positions shown in Fig. 4. 45

The pawl 69 is also restored to its home position shown in Fig. 4, by the camming engagement of the inclined face 143 of projection 69a with the inclined face 144 of the notch 124. As the pawl tooth 72 is shown in Fig. 5 as only partially within a space between clutch disk teeth 59, the projection 86 of its clutch ring 75 will engage the bail 87 somewhat after the projection 85 and consequently the degree of movement required to restore the pawl 69 to its home position shown in Fig. 4 will be substantially less than was required to restore pawl 68. It will be apparent that instead of the tooth 70, had the pawl tooth 72 been in full clutching engagement with the teeth of the disk 58, the projection 86 would have engaged the bail 87 first and the pawl tooth 72 moved thereby the greater distance sufficient to be disengaged from the disk 58 and restored to home position. The clutch 52 is disengaged and the pawls 68 and 69 restored to the home position shown in Fig. 4 just as the magnet 50 reaches its home position. The detent 104 cooperating with the recess 106 in the cam plate 79, serves to position and hold the parts in their home position in the manner previously described. 50

The apparatus disclosed herein as being one

preferred embodiment of this invention, also comprises a series of armatures disposed in circumferentially spaced relation about the axis of rotation of the magnet 50. The clutch latch armature 95 described above as being in attracting relation with respect to the magnet when at home position, may be considered as one of this series of armatures. The other armatures of the series are indicated by the reference characters 146, 147, 148, and 149. Thus, there are altogether five armatures composing the series and they correspond, respectively, to the five index point positions of the selected code system previously described. The armatures are so spaced circumferentially and the driving mechanism for the tape feeding roll 20 and the magnet 50 so designed, that as the magnet rotates it occupies successively attracting positions with respect to the armatures and synchronously with the sensing of their corresponding index point positions.

The armatures 146, 147, 148, and 149 are pivoted to studs 150, 151, 152, and 153, respectively, carried by the support plate 22, and these armatures are formed with latching arms 154, 155, 156, and 157 which cooperate, respectively, with latching arms 158, 159, 160, and 161, respectively. The latter latching arms form parts of contact carrying members 162, 163, 164, and 165, respectively, which are pivoted on the studs 99, 106, 150, and 151 carried by the plate 22. A tension spring 168 connects each of the armatures 146, 147, 148, and 149 with its related one of the cooperating latching arms 158, 159, 160, and 161. The tension springs 168 serve to move the latching arms 154, 155, 156, and 157 of the armatures into latching engagement with their related latching arms 158, 159, 160, and 161 and to hold them in latching engagement after they are latched. The tension springs 168 also serve to shift their related contact carrying members clockwise, as viewed in Fig. 1, when unlatched by the related armatures 146, 147, 148, and 149 being attracted by the energizing of the magnet 50 while occupying an attracting position with respect thereto.

The above described coaction of the armatures 146, 147, 148, and 149 and their related contact carrying members 162, 163, 164, and 165 can best be understood by referring to Fig. 3. Reference may also be had to Fig. 9 which is a detail view showing the armature 146 and its related contact carrying member 162 apart from the other elements of the apparatus. The armature 146 and member 162 are shown in Fig. 3 and Fig. 9 in their unlatched or tripped relation. As Fig. 3 shows the rotating parts in their home position with the clutch latch armature 95 and secondary latch lever 88 in their latched position, it should be assumed that the armature 146 was tripped on the previous revolution of the magnet 50.

During each revolution of the magnet 50, any of the armatures 146, 147, 148 and 149, which was tripped on the previous revolution of the magnet, is relatched with respect to its coacting contact carrying member, before the magnet reaches an attracting position with respect to such armature. As shown in Fig. 3, each of the contact carrying members is provided with an inwardly extending re-latching arm 170 which, when its contact carrying member is tripped and shifted by its related spring 168 into unlatched position, is moved thereby into the path of a pin 171 carried by the cam plate 79 (see also Fig. 1). With the parts in the position shown in Figs.

1 and 3 and upon the starting of a revolution by the magnet 50, the pin 171 will engage the re-latching arm 170 of the member 162 and move the latter counterclockwise about the stud 99. 5 When the latter occurs, the spring 168 will move the armature 146 clockwise about the stud 150 and a latching projection 173 on the end of the arm 158 will engage a notch 174 on the end of arm 154. As the latter occurs, the pin 171 passes 10 out of engagement with the arm 170 and the parts are held in their latched relation by their related spring 168.

After the just described relatching operation has been effected, the magnet 50 will move into 15 attracting position with respect to the armature 146. It will be apparent that the pin 171 will also engage and move the re-latching arm 170 of any of the remaining contact carrying members which has been previously tripped, so as to effect 20 the relatching of the latter with respect to its related armature before the magnet moves into attracting position with respect to such armature.

When the magnet 50 occupies an attracting 25 position with respect to any of the armatures 146, 147, 148, and 149 and upon the energizing of the magnet while occupying such a position, the armature in attracting relation with respect to the magnet is attracted thereby and is moved 30 counterclockwise, as viewed in Figs. 1, 3, and 9, to trip or unlatch such armature and its related contact carrying member. The latter is shifted clockwise to its tripped position by its related spring 168. It is noted that each of the arms 35 154, 155, 156, and 157 of the armatures is formed with a shoulder 175 which is engaged by the end 173 of its related contact carrying member when the latter moves to its tripped or shifted position. Thus, the shoulders 175 limit the clockwise 40 movement of their related contact carrying members and thereby determine the tripped position of such contact carrying member.

Fig. 12 shows diagrammatically an electrical 45 circuit means which operates in response to the sensing means previously described and provides for the selective energizing of the magnet 50 and the consequent selective actuation of the five armatures 95, 146, 147, 148, and 149 in accordance with the number and differential positioning of the code designations of each character representation. The magnet 50, armatures 95, 146, 147, 148, and 149 and the contact carrying members 162, 163, 164, and 165 are also shown somewhat diagrammatically in Fig. 12 in order that 55 their operation might be more readily understood.

With the manual power switch 200 closed and the magnet 50 in the home position shown, the filament 201 of the high vacuum amplifier tube 60 202 is connected across a suitable source of direct current. The source is represented herein by a positive supply wire 203 and a negative supply wire 204. With the switch 200 closed and with the magnet in attracting position with respect to one of the armatures, the coil of the magnet 50 is connected in the plate circuit of the tube 202, which circuit may be traced as follows: From the positive supply wire 203, wire 205, point 206 of commutator segment 207, brush 208, 65 wire 209, coil of magnet 50, wire 210, brush 211, point 212 of commutator segment 213, wire 214, anode 215, cathode 216, wire 217, switch 200, and to the negative supply wire 204. A suitable battery 220 provides a normal negative bias on 70 75 the control grid 221 of the tube 202 and there-

by serves to prevent normally the flow of sufficient current in the plate circuit to energize the magnet 50.

The sensing elements 13 and 14 and the two wires 44 and 48 previously referred to, are shown diagrammatically, the element 14 being connected through the wire 44 to the wire 217 and the negative supply wire 204, and the element 13 being connected through the wire 48 to the control grid 221. From the previous description, it will be apparent that with power shaft 25 in operation and the tape 18 being fed by the roller 26, the five index point positions 17 of each of the character representations pass successively the sensing elements 13 and 14. As stated previously, each character representation includes a bar 15 in the first index point position. With the parts in the home position shown in Fig. 12 and when a bar 15 in the first index point position of a character representation is sensed, the control grid 221 is connected through the elements 13 and 14 and the sensed bar 15 directly to the negative side of the line and to the cathode 216, thus reducing the negative bias on the control grid 221 to a point where sufficient current will flow in the plate circuit previously traced, to energize the magnet 50.

As will be apparent from the previous description, when the magnet 50 is energized in the home position shown, the clutch latch armature 95 is attracted and thereby trips the secondary latch 88 and effects the engagement of the one revolution clutch 52 which provides for the rotation of the magnet 50. As the magnet 50 moves from attracting position with respect to the armature 95 and successively into attracting positions with respect to the remaining armatures 146, 147, 148, and 149, the remaining four index point positions of the character representation being sensed, pass synchronously beneath the sensing elements 13 and 14.

The apparatus disclosed also advantageously includes a means which provides for the flow of current through the coil of the magnet only when the latter occupies an attracting position with respect to any of the armatures and prevents flow of current to the magnet when the latter is not in attracting position with respect to an armature. As shown, this means comprises the two stationary commutator segments 207 and 213 and the two brushes 208 and 211 which are carried by the bracket 115 and thereby rotate with the magnet 50. The segments 207 and 213 are secured to the post 90 and a second post 225 carried by the support plate 22. There are five points 206 provided on the segment 207 and five points 212 on the segment 213. These points correspond, respectively, to the five armatures. The points 206 and 212 are so spaced on their respective segments that the brushes 208 and 211 contact the points 206 and 212, respectively, only when the magnet 50 is in attracting relation with respect to their related armature. Thus, the coil of the magnet 50 is connected in the plate circuit of the tube 202 only when the magnet is in attracting position with respect to an armature.

From the foregoing, it is apparent that as each character representation is sensed the magnet 50 is selectively energized so as to provide different conditions of selective actuation of the armatures, and such conditions represent, respectively, the character representations sensed. For example, if the character representing the digit "3" is sensed, the magnet 50 is energized when the bar 15 in the first index point position of the

character representation corresponding to the digit "3," passes beneath the sensing brushes 13 and 14. As stated above, this starts the rotation of the magnet 50 while the bar 15 in the first index point position is still under the sensing elements 13 and 14. As the character representation for the digit "3" also comprises a bar 15 in the second and fifth index point position, the armature 148 will also be attracted when the magnet 50 occupies an attracting position with respect thereto and the armature 148 will be attracted when the magnet 50 occupies an attracting position with respect thereto. Thus, when the character representation for the digit "3" is sensed the magnet 50 selectively actuates the first, second and fifth armatures synchronously with the sensing of a bar 15 in each of the first, second, and fifth index point positions of the character representation and this action provides a condition of selective actuation of the armatures which corresponds to the character representation for the digit "3" in accordance with the selected code system.

When, for example, the character representation for the digit "4" is sensed, a bar 15 in the first index point position will be sensed and the magnet will rotate for a complete revolution without actuating any of the other armatures, with the result that only the first or clutch latch armature 95 will have been actuated. Thus, the latter action also provides a condition of selective actuation of the armatures which corresponds to the digit "4" in accordance with the selected code.

In accordance with certain aspects of the present invention, a means is also provided which functions to manifest the characters which are sensed and represented by the corresponding conditions of selective actuation of the armatures as explained above. The manifesting means is controlled by the armatures and in the apparatus disclosed comprises a translator including the contact carrying latch members 162, 163, 164 and 165 described above and also including an electrical circuit network controlled by the contacts carried by such latch members and providing, for each condition of actuation of the armatures, a work circuit including a work magnet operable to manifest the character represented by the condition of actuation of the armatures and sensed by the sensing elements.

In Fig. 12, the work magnets corresponding to the digits "0" through "9" are indicated by corresponding legends and by the reference characters 230, 231, 232, 233, 234, 235, 236, 237, 238, and 239, respectively, and the circuit wires leading to such magnets are indicated by the reference characters 240, 241, 242, 243, 244, 245, 246, 247, 248, and 249, respectively. The work magnets 230 to 239 inclusive represent the controlling elements of any suitable manifesting mechanism; such for example, as a tabulating card punch of the type disclosed in the Brand patent, above identified. The work magnets shown in Fig. 12 are intended to be the same as those indicated by the reference character "145" in the Brand patent referred to. As the structure and operation of card punches of this type are well known to those skilled in this art, a more detailed disclosure thereof herein is considered to be superfluous.

The apparatus disclosed herein operates in successive cycles, each cycle being represented by a revolution of the magnet 50. During the first part of each cycle, the character representation 70 is sensed and the armatures selectively actuated

in the manner previously explained. During the latter part of each cycle, the character represented by the condition of selective actuation of the armatures is manifested by energizing the work magnet corresponding thereto. As will be apparent from the foregoing description, at the end of the character sensing portion of a cycle, each of the contact carrying members 162, 163, 164, and 165 occupies either one of two positions depending upon whether or not its related armature has been attracted while the character representation was being sensed. The two positions of each member may be termed the latched position and the tripped position, respectively. All of the contact carrying members are shown in their latched position in Fig. 12 and the member 162 is shown in its tripped position in Fig. 1.

Each contact carrying member carries a set of spaced contacts which, when in latched position, engage, respectively, a corresponding number of spaced stationary contacts and which, when in the tripped position, engage, respectively, another set of spaced stationary contacts. As shown in Figs. 1, 2, and 12, the movable contact carrying latch member 162 carries three spaced contacts 251, 252, and 253, respectively, which when the member 162 is in latched position engage, respectively, the stationary contacts 254, 255, and 256 which are fixed to a segmental shaped member 257 formed of suitable insulation material and mounted on the support plate 22. When the member 162 is shifted to its tripped position (see Fig. 1) the movable contacts 251, 252 and 253 carried thereby engage, respectively, spaced stationary contacts 258, 259, and 260 which are also carried by the fixed insulation member 257.

Similarly, the contact member 163 carries a pair of movable contacts 261 and 262 which engage spaced stationary contacts 263 and 264, respectively, when in latched position and engage spaced stationary contacts 265 and 266 when in tripped position. Member 164 carries three spaced contacts 269, 270, and 271, respectively, which engage a set of stationary contacts 272, 273, and 274, respectively, when in latched position and engage a second set of stationary contacts 275, 276, and 277, when in tripped position. The contact carrying member 165 carries two spaced movable contacts 280 and 281; but in the circuit network shown it is only necessary to use the contact 280. The contact 280 engages the stationary contact 282 when the member 165 is latched and the stationary contact 283 when the member 165 is shifted to its tripped position.

The stationary contacts mounted on the member 257 and the movable contacts on the several contact carrying members are so interconnected by circuit wires that they establish for each condition of selective actuation of the armatures, a work circuit including a work magnet which when energized manifests the character corresponding to such condition of selective actuation and to the character representation sensed. The work circuit is established during the sensing portion of each cycle which terminates with the magnet moving past attracting position with respect to the fifth or last armature 149. During the remaining portion of the cycle, the established work circuit is closed and the character sensed during the first part of the cycle, is manifested. The closing of the work circuit is effected by a cam 285 engaging and closing a pair of contacts 286. The cam 285 is formed of a suitable insulating material and is secured by suitable studs 287 to the cam plate 79 on which the magnet 58

is mounted. The contacts 286 are suitably mounted on a bracket 288 carried by the fixed support plate 22.

The work circuit corresponding to each of the digit characters "0" through "9" can be readily traced on Fig. 12. Fig. 13 is a chart showing the armatures which are actuated when character representations of each of the ten digits are sensed. From an examination of Fig. 13, it is noted that only the armature 85 is actuated when the digit "4" is sensed. From the previous description it is known that the energizing of the magnet 58 while in home position actuates the armature 85 and operates the one-revolution clutch to rotate the magnet 58 for one complete revolution. As none of the remaining armatures are actuated when the digit "4" is sensed, the contact carrying members 162, 163, 164, and 165 will remain in the position shown in Fig. 12. When the cam 285 closes the contacts 286 during the latter portion of the cycle the work circuit including the work magnet 234 for the digit "4" is closed. The latter circuit is traced as follows: from the negative supply wire 204, a wire 290, contacts 286, a wire 291, movable contact 280, stationary contact 282, a wire 292, movable contact 262, stationary contact 264, a wire 293, movable contact 253, stationary contact 256, a wire 294, movable contact 271, stationary contact 274, work circuit wire 244, work magnet 234, common wire 295, and wire 296 to the positive supply wire 203.

As described above when the character representation for the digit "3" is sensed, armatures 85, 146, and 149 are tripped, and contact carrying members 162 and 165 are shifted from their latched position shown in Fig. 12 to their tripped position. This will establish a work circuit including the work magnet 233 which circuit will be closed by the cam 285 during the latter portion of the cycle. The latter work circuit is traced as follows: negative wire 204, wire 290, contacts 286, wire 291, contacts 280 and 283, a wire 297, contacts 261 and 263, a wire 288, contact 251, contact 258, work circuit wire 243, work magnet 233, and wires 295 and 296 to the positive wire 203.

With the above explanation, it is believed that the work circuits corresponding to the other conditions of selective actuation of the armatures and the characters sensed, can be readily traced on Fig. 12 when considered with Fig. 13.

While there have been shown and described and pointed out the fundamental novel features of the invention as applied to a preferred embodiment, it will be understood that various omissions and substitutions and changes in the form and details of the device illustrated and in its operation may be made by those skilled in the art, without departing from the spirit of the invention. It is the intention, therefore, to be limited only as indicated by the scope of the following claims.

What is claimed is:

1. In a cyclically operable unit for receiving during each cycle a character representation transmitted thereto as electrical impulses differentially timed in accordance with a predetermined code system having a selected number of code positions and with the timing of the impulses corresponding to the code positions, the combination of an electromagnet mounted for rotation at a given time rate about a fixed axis with each revolution thereof corresponding to a cycle of operation, and said magnet including a coil adapted to be energized by said impulses

and constructed and arranged so that its attracting force acts in a direction extending substantially radially inward toward the rotary axis of said magnet; a plurality of armatures corresponding, respectively, to the positions of said code system and being circumferentially disposed about said magnet and so spaced from one another that as said magnet is rotated during each cycle the latter successively occupies attracting positions with respect to the armatures and synchronously with the receiving of the electrical impulses; each of said armatures being supported for pivotal movement about an axis extending parallel to said rotary axis and the pivotal axes of the several armatures being circumferentially spaced about said rotary axis; a separate latch member for each said armature and each latch member being pivotally mounted to move about an axis arranged parallel to said rotary axis and the pivotal axes of said latch members being disposed about said rotary axis in circumferentially spaced relation; each armature and its related latch member coacting with one another to occupy a normal latched position before such armature is attracted by said magnet and each armature and its related latch member being movable to unlatched positions upon being attracted by said magnet.

2. In a cyclically operable unit for receiving during each cycle a character representation transmitted thereto as electrical impulses differentially timed in accordance with a predetermined code system having a selected number of code positions and with the timing of the impulses corresponding to the code positions, the combination of an electromagnet mounted for rotation at a given time rate about a fixed axis with each revolution thereof corresponding to a cycle of operation, and said magnet including a coil adapted to be energized by said impulses and constructed and arranged so that its attracting force acts in a direction extending substantially radially inward toward the rotary axis of said magnet; a plurality of latchable armatures corresponding, respectively, to the positions of said code system and being circumferentially disposed about said magnet and so spaced from one another that as said magnet is rotated during each cycle the latter successively occupies attracting positions with respect to the armatures and synchronously with the receiving of the electrical impulses; each of said armatures normally occupying a latched position and being movable to an unlatched position when attracted by said magnet; and latching means movable with said magnet and operable during each cycle to restore armatures unlatched during a previous cycle, to their latched positions before said magnet moves into attracting position with respect to such armatures.

3. In a cyclically operable unit for receiving during each cycle a character representation transmitted thereto as electrical impulses differentially timed in accordance with a predetermined code system based on a selected number of code positions and with the timing of the impulses corresponding to the code positions, the combination of a power shaft; means for rotating said shaft at a fixed time rate; an electromagnet supported for rotation about a given axis and including a coil adapted to be energized by said

impulses and being so constructed and arranged that its attracting force acts in a direction extending inward toward the rotary axis of said magnet; detent means positioning said magnet at a home position; clutch means operable to connect said magnet to said shaft for rotating said magnet for one revolution beginning and ending at said home position and corresponding to one operating cycle, and operable to disconnect said magnet and shaft upon return to said home position; a plurality of armatures corresponding, respectively, to the positions of said code system and being circumferentially disposed about said magnet and so spaced from one another that as said magnet is rotated during each cycle it successively occupies attracting positions with respect to said armatures and synchronously with the reception of the electrical impulses; and means for operating said clutch means at the beginning of the reception of a character representation.

4. Apparatus according to claim 3 wherein one of said armatures is in position to be attracted by said magnet when the latter occupies its home position and wherein said clutch means is operated by said one armature when attracted.

5. Apparatus according to claim 3 wherein said armatures, respectively, comprise lever arms pivoted to move about axes extending parallel to and circumferentially spaced about the rotary axis of said magnet.

6. Apparatus according to claim 3 wherein said clutch means comprises a pair of rotary driving and driven elements coaxially arranged with respect to one another and with respect to the rotary axis of said magnet and a pawl carried by one of said elements and movable to effect operative engagement and disengagement of said elements; and said magnet being secured to said driven element and rotatable therewith.

7. In a cyclically operable unit for receiving during each cycle a character representation transmitted thereto as electrical impulses differentially timed in accordance with a predetermined code system having a selected number of code positions and with the timing of impulses corresponding to the code positions, the combination of an electromagnet adapted to be energized by said impulses and being mounted for rotation at a given time rate about a fixed axis with each revolution thereof corresponding to a cycle of operation; a plurality of latchable armatures corresponding, respectively, to the positions of said code system and being circumferentially disposed about the axis of rotation of said magnet and being so arranged and spaced with respect to one another and to said magnet that as said magnet is rotated during each cycle the latter successively occupies attracting positions with respect to the armatures and synchronously with the receiving of corresponding electrical impulses; each of said armatures normally occupying a latched position and being movable to an unlatched position when attracted by said magnet; and latching means movable with said magnet and operable during each cycle to restore armatures unlatched during a previous cycle to their latched positions before said magnet moves into attracting position with respect to such armatures.
